DAY AND NIGHT ILLUMINATED PLATE
FOR SIGNS

John M. Moore, New York, N. Y.

Application April 12, 1934, Serial No. 720,237

2 Claims. (Cl. 40—133)

This invention relates to new and useful improvements in a day and night illuminatable plate for signs, useable as a license plate, advertising sign or the like.

5 The invention has for an object the construction of a plate for signs to be illuminated from the rear which is characterized by a front opaque background member having stenciled character openings and a back transparent, semi-transparent or translucent member to cover the character openings. With this arrangement upon illumination of the back of the sign it may be readily seen.

10 Still further the invention particularly proposes an arrangement whereby the back member is provided with raised characters engaging into the character openings of the front member and said raised characters being of the same material as the back member and having its face flush with the front face of the front member. This arrangement is of importance in that then the front of the plate is absolutely smooth and may readily be kept clean merely by washing.

15 20 25 Still further the invention also proposes an arrangement where symbols are used in conjunction with the character openings so as to enhance the value of the plate, for example, such symbols may be small red areas at the upper corners of the plate to act as a warning sign so that following vehicles do not come too close.

Still further the invention also proposes the construction of a casing for holding the plate which is characterized by a box having an open front and a reflector mounted in the back and having opposed inclined sides and opposed inclined top and bottom portions connected with a rear portion parallel to the front and illuminated with an opposed pair of lights in a manner so as to efficiently illuminate the rear of the plate.

30 35 40 45 Still further the invention also proposes an arrangement whereby opaque slides are adjustably mounted upon the rear of the back member of the plate and adapted to cover the transparent symbols if desired.

Still further the invention also proposes the provision of additional lamps for illuminating the reflector and arranged in a circuit and controlled by the action of said slides in a manner so that one pair of lamps illuminate the additional symbols, when the latter elements 45 50 55 are operated and when the slides cover up these

elements, then another pair of lamps operate to illuminate the rear of the plate.

Still further the invention proposes the construction of a device as mentioned which is simple and durable and which may be manufactured and sold at a reasonable cost.

5 10 15 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

15 Fig. 1 is a perspective view of a device constructed according to this invention.

Fig. 2 is a front elevational view of Fig. 1 shown with the front cover and plate removed.

20 Fig. 3 is a sectional view taken on the line 3—3 of Fig. 1.

Fig. 4 is a horizontal sectional view taken on the line 4—4 of Fig. 2.

25 Fig. 5 is a perspective view similar to Fig. 1 but illustrating another embodiment of the invention.

Fig. 6 is a fragmentary horizontal sectional view taken on the line 6—6 of Fig. 5.

30 Fig. 7 is a fragmentary horizontal sectional view similar to Fig. 6 but illustrating a modification of the invention.

Fig. 8 is a rear elevational view of Fig. 7 seen as though looking in the direction of the line 8—8 of Fig. 7.

35 Fig. 9 is a fragmentary elevational view of a casing for the plate illustrated in Figs. 7 and 8.

Fig. 10 is a schematic diagram of the device.

The day and night illuminable plate for signs according to this invention comprises a front opaque background member 10 having stenciled character openings 11, and a back transparent, semi-transparent, or translucent member 12 having raised characters 13 engaging in said stenciled character openings 11 and of the same material as the back member. These characters 13 completely close the character openings 11 and are so constructed that the outer faces are flush with the outer face of the front member 10. It is intended that the front and rear members should be made of desirable materials such as phenol compensation products or metals. If phenol compensation products are used it is advisable that the front and rear members be joined by the use of solvents. Adjacent contacting surfaces should be 50 55 60 65 70 75 80 85 90 95 100

treated with the solvents so that they become soft and then engaged with each other and allowed to dry. With this arrangement the plate will be of one integral piece when finished.

5 In addition to the stenciled characters 13 guide symbols may be incorporated in the plate such as the symbols 14. These symbols 14 are small areas of transparent, semi-transparent or translucent material, but red in color. They are 10 intended to denote danger so that vehicles to the rear of one provided with the plate will not come too close. These symbols 14 are constructed very similar to the characters. More particularly the front member 10 is formed 15 with symbol openings 15 into which the symbols 14 project. The symbols 14 are mounted upon the back member 12. Preferably the symbols 14 should be of the same material as the back member varying only in color. A very nice 20 arrangement for the plate is one in which the characters 13 and the back member 12 are of yellow color, and the symbols 14 of red color.

The plate is used in conjunction with mechanism whereby the rear of the plate may be illuminated. This mechanism comprises a casing 16 having a front opening closed with a reflector containing various reflecting surfaces and comprising opposed side surfaces 17 opposed top and bottom surfaces 18 and a rear surface 19 parallel to the plate of the open front of the casing. A pair of opposed lamps 20 are mounted upon the opposed sides 17 of the reflector near the top so as to be located directly behind the symbols 14. A frame 21 is 30 adapted to engage over the open front of the casing 15 and hold the plate 10 in position. The lamps 20 are electrically connected with a cable 22' extending at the point 22 from the casing and intended to be connected with a source of 35 power such as the battery 23, schematically illustrated in Fig. 1. A feature of the arrangement is that the light from the lamps will be reflected by the various reflecting surfaces 17, 18 and 19 against the rear of the plate 10 so as to illuminate the characters 13 and the symbols 14. The main portion of the plate 10 is opaque so that the illuminated portions will stand out vividly.

In Fig. 5 another embodiment of the invention has been disclosed in which a plate 10' is shown constructed identical to the plate 10 differing merely in the characters. In Fig. 1 the characters represent a license plate. In Fig. 5 the characters represent a sign bearing the words "To let." The plate 10' is formed with stenciled character openings 11' into which the characters 13' project. These characters 13' are arranged upon a transparent, semi-transparent or translucent back member 12. From this brief description it is believed that the construction will be readily understood.

Another variation in the form of the invention illustrated in Fig. 5 is in the arrangement of the casing 16 which is provided with a pair of legs 16' so that the sign may be supported or rested upon a flat surface. At the point 22 a cable 22' extends from the device for connection with a source of electrical current.

In Figs. 7-10 inclusive another variation of the invention has been disclosed wherein there is a plate 10 constructed substantially identical to the corresponding plate illustrated in Fig. 1 and shown provided with symbol portions 14'. These symbol portions are of transparent, semi-transparent or translucent material and of red

color for the purpose described relative to the corresponding portions 14. For each of the symbol portions 14' there is provided a slide 25 adjustably supported by a pair of screws 26 upon the rear of the back member 12. Each 5 slide 25 is adapted to assume an open position as illustrated upon the drawing or to assume a closed position indicated by the dot and dash lines in Fig. 7 which position the slide extends over and covers the back of the symbol 14'. 10 A pair of self opening switches 27 and 28 are used in conjunction with one slide 25 and are mounted upon the back member 12. One of these switches 27 is arranged at a point so as to normally be held closed when the slide 25 is 15 in the open position. The other switch 28 is arranged at a point so as to be closed when the slide 25 is moved to the closed position. Upon motion of the slide 25 to the closed position the switch 27 will be released and automatically 20 open.

The type of plate shown in Figs. 7 and 8 is intended to be used with a casing 16 having a reflector 17, 18 and 19 in which there are provided top lamps 20 arranged immediately behind the symbols 14' to illuminate the symbols 14' and central lamps 29 arranged at the center of the reflector to be used to illuminate the back of the plate, as a substitute for illumination by the lamps 20. It is intended that the lamps 20 30 be used for the illumination of the plate when the symbols 14' are in operation. But when the symbols 14' are not in operation then it is intended that the lamps 29 be used to illuminate the plate. The lamps 20 are connected in series 35 with the switch 27 and in parallel with a power circuit 30. The lamps 29 are connected in series with the switch 28 and in parallel with the power circuit 30. In the condition of the device as illustrated on the drawing, the switch 27 is closed 40 and the lamps 20 are operating to illuminate the back of the plate and symbols 14'. When the slides 25 are moved into positions to cover up the symbols 14' then the switch 27 will be opened, and the switch 28 will be closed so that 45 the central lamps 29 are now operating and the top lamps 20 are out of operation.

While I have shown and described the preferred embodiment of my invention, it is to be understood that I do not limit myself to the 50 precise construction herein disclosed and the right is reserved to all changes and modifications coming within the scope of the invention as defined in the appended claims.

Having thus described my invention, what I 55 claim as new, and desire to secure by United States Letters Patent is:—

1. A day and night illuminable plate for signs, comprising a front opaque background member of phenol condensation material having character openings, and a back translucent member upon the back of said front member and also of phenol condensation material and integrally joined therewith with solvents.

2. A day and night illuminable plate for signs 65 comprising a front opaque plate of phenol condensation material having character openings, and a back translucent member of phenol condensation material having like characters in relief upon the front of said back member so 70 as to be cooperable with said character openings, said front plate and said back members being integrally joined by temporary solution of their contacting parts.
